UNITED STATES PATENT OFFICE.

JULIUS FRECSKA, OF AMSTERDAM, OHIO, ASSIGNOR OF ONE-HALF TO ZIGMOND FRECSKA, OF AMSTERDAM, OHIO.

AERIAL TORPEDO.

1,339,188.

Specification of Letters Patent.

Patented May 4, 1920.

Application filed November 20, 1918. Serial No. 263,375

To all whom it may concern:

Be it known that I, JULIUS FRECSKA, a citizen of the United States, residing at Amsterdam, in the county of Jefferson and 5 State of Ohio, have invented new and useful Improvements in Aerial Torpedoes, of which the following is a specification.

This invention relates to aerial torpedoes for use in warfare, the broad object in view 10 being to produce a torpedo which will sustain itself in continuous flight after being launched into the air.

One of the main objects of the invention is to produce a torpedo embodying an aerial 15 supporting surface, which surface is initially folded and automatically spread by the flight of the torpedo. This enables the torpedo to be fired from a gun or other fire arm, the aerial supporting surface being spread after the torpedo emerges from the barrel of such gun or fire arm.

A further object in view is to produce a torpedo embodying a shell composed of leading and trailing sections some of which contain 25 propelling charges such as slow burning powder, said sections being separably connected so that any desired number of trailing sections may be employed in accordance with the length of flight of the 30 torpedo. In the preferred embodiment of the invention, the shell sections which contain the propelling charges are connected by fuses thereby enabling the charge carrying sections of the shell to operate successively.

35 With the above and other objects in view, the invention consists in the novel construction, combination and arrangement herein fully described illustrated and claimed.

In the accompanying drawings:—

40 Figure 1 is a plan view showing the aerial supporting surface folded.

Fig. 2 is a similar view showing the aerial supporting surface spread.

45 Fig. 3 is a longitudinal section through the complete torpedo.

Fig. 4 is a fragmentary longitudinal section taken through the leading section and showing the supporting surface folded.

50 Fig. 5 is a similar view showing the supporting surface spread.

Fig. 6 is a transverse section through the torpedo taken adjacent to the junction between the leading section and the next trailing section.

Fig. 7 is a perspective view of one of the 55 wing structures.

In carrying out the present invention, in the preferred embodiment thereof, I employ a shell comprising a leading section 1 and a plurality of trailing sections 2, all of 60 said sections being separably connected so that any desired number of sections may be employed according to the length of flight of the torpedo. The leading section 1 and the next following trailing section 2 may be 65 permanently connected together by a joint 3 of any suitable type. The remaining trailing sections 2 are connected together by a separable slip joint 4, enabling said sections to be easily assembled and separated. The 70 slip joints 4 are preferably of the rabbeted type as shown.

Each of the trailing sections 2 contain a propelling charge 5 of slow burning powder for example, having the same propelling 75 effect on the shell of the torpedo as the charge of the well known sky-rocket. If desired, a high explosive charge may be placed in the rearmost section 2, to adapt the whole device to be placed in a gun in a manner 80 similar to an ordinary cartridge as placed in the breech of a fire-arm, such explosive charge being utilized to project the remainder of the torpedo into space. The trailing sections 2 are provided at their rear 85 ends with heads 6, and a combined tube and vent tube 7 is inserted through each of said heads thus avoiding communication between the several sections 2. The foremost trailing section 2 in the preferred embodiment 90 of the invention will be somewhat longer than the remaining trailing sections in order that a highly explosive charge 8 may also be contained therein for the purpose of exploding the torpedo after it reaches the 95 enemy. One of the trailing sections 2 and preferably the foremost trailing section is provided with an aerial supporting surface and such supporting surface is preferably in the form of oppositely extending wing 100 surfaces 9, each being shown as composed of wing bars 10 and ribs 11, said bars and ribs being inclosed by upper and lower surfaces 12 of fabric or any other suitable material such as that employed in the construction of the wings on airplanes. In order to provide for folding and spreading the wing surfaces herein above referred to,

the said trailing section of the shell of the torpedo is provided on each side thereof with longitudinally extending flanges 13 arranged in spaced relation to each other and forming a channel for the reception of a plurality of wing supporting arms 14 which are connected by pivots 15 to the adjacent inner edges of the supporting wing. Said arms are connected by pivots 16 to the said 10 trailing section of the torpedo as shown in the drawings, said supporting arms being adapted to pull into the channels between the flanges 13. The construction of each wing structure is such that the same 15 is adapted to be folded within the channels referred to, thereby enabling the complete structure to be placed in the barrel of a gun or fire arm preparatory to projecting the same into space. The leading section of the 20 torpedo may be allowed to project beyond the barrel of the gun or fire arm and also a portion of the foremost trailing section of the torpedo.

The means for spreading the aerial supporting surface or in other words, the wings, 25 comprises a fluid pressure operated device or member 17 mounted at the forward end of the torpedo body and passed upon a propeller shaft 18 which is threaded and constitutes a feed screw for the purpose hereininafter specified. The shaft or feed screw 18 extends longitudinally into the leading section 1 of the shell, being supported in suitable bearings therein and having a 30 threaded connection with a traveler 19 movable longitudinally within said leading shell section. The traveler 19 is substantially U-shaped, comprising oppositely and rearwardly extending arms 20 coupled by suitable connecting means such as rods 21 with pivoted wing supporting arms hereinabove described. For the purpose of connecting the rods 21 with the arms 14, the latter may be formed with longitudinal slots 22 35 through which the rods 21 pass, said rods being provided with heads or shoulders 26 working against the rear side of the arms 14. The operation of this portion of the mechanism may be described as follows: 40 When the torpedo is fired from a gun or other fire arm, rotary motion is imparted to the wheel or propeller 17 by air pressure against the same. This in turn rotates the feed screw 18 and the latter causes a forward movement of the traveler 19, as the latter is connected by the means described with the wing supporting arms 14, said arms are swung outwardly from their folded position and the aerial supporting 45 surfaces or wings are thus automatically spread while the torpedo is in actual flight.

From the foregoing description taken in connection with the accompanying draw-

ings it will now be understood that the aerial torpedo is adapted to be fired from any suitable gun or fire arm while the supporting surfaces or wings are folded. The length of flight is governed by the number of trailing sections employed as they will be ignited one after another thus prolonging the flight to any desired extent. When the shell emerges from the barrel of the fire arm, the wing spreading means begin to operate and in a short time the wings are fully spread so as to support the torpedo in flight after the initial velocity of the torpedo has been reduced. When the torpedo reaches its destination, the explosive charge 8 bursts the remainder of the torpedo with the desired effect in the ranks of the enemy. 80

I claim:—

1. An aerial torpedo comprising a plurality of sections arranged in tandem formation, a propelling charge in one section, an initially fixed aerial supporting surface, and wing spreading means carried by one section and operated by the flight of the torpedo. 85

2. An aerial torpedo comprising a plurality of sections arranged in tandem formation, a propelling charge in one section, an initially folded aerial supporting surface, and wing spreading means carried by one section and operated by the flight of the torpedo, said means embodying a fluid pressure actuated member connected with said supporting surface. 95

3. An aerial torpedo comprising a plurality of sections arranged in tandem formation, a propelling charge in one section, an initially folded aerial supporting surface, and wing spreading means carried by one section and operated by the flight of the torpedo, said means embodying a rotary air pressure operated device to actuate said member, and a feed screw driven by the last named member and connected with said supporting surface. 100

4. In an aerial torpedo, a body, initially folded aerial supporting members pivotally connected with said body at opposite sides thereof and including arms, a screw rotatably mounted at the forward end of said body, a U-shaped yoke having its bight portion threadedly receiving said screw and having its arms engaging the arms of said aerial supporting members, and a propeller secured upon the forward extremity of the screw whereby the flight of the torpedo will cause rotation of the propeller to move said yoke for moving said aerial supporting members to extend laterally beyond the body. 115

In testimony whereof I affix my signature.

JULIUS FRECSKA.
